UNITED STATES PATENT OFFICE

2,140,494

REEL

Ralph W. Clemons, Chicago, Ill., assignor to
 R. B. Hayward Company, a corporation of Illinois

Application May 3, 1937, Serial No. 140,506

3 Claims. (Cl. 242—77)

My invention relates to reels provided, for example, for the winding thereon of electric cable, or the like, and more particularly to reels formed of spaced apart heads and an interposed drum portion of metal secured thereto, as for example by tie rods extending from head to head through inwardly extending portions at the ends of the drum.

My object, generally stated, is to improve upon constructions of reels of the character above referred to as hitherto provided to the end of producing a construction which will afford better service and be more economical of manufacture and of lighter weight, than constructions as hitherto provided.

More specifically stated, one of my objects is to provide a construction whereby the cylindrical side-wall of the drum may be constructed of high carbon sheet steel presenting such high degree of stiffness as to be immune from denting in use even when provided of relatively light gauge, such as for example No. 16 gauge and which may be used to advantage in cable reels of drum diameters of approximately 48 inches or less and load capacities up to approximately 6 tons; and provide for high resistance of the drum structure to shear.

Another more specific object is to provide a structure having the attributes just described which will present the desired rigidity and which may be fabricated at the minimum expense.

Referring to the accompanying drawings:

Figure 1 is a view in side elevation of a reel embodying my invention.

Figure 2 is an end view of the same.

Figure 3 is an enlarged fragmentary sectional view taken at the line 3 on Fig. 2 and viewed in the direction of the arrow.

Figure 4 is an end view of the drum forming a portion of the reel.

Figure 5 is a similar view of a modification of the drum structure; and

Figure 6, a fragmentary sectional view of the structure of Fig. 5 showing a detail thereof.

Referring to Figs. 1-4 of the drawings, the construction shown therein comprises a pair of circular heads 7 and 8, each shown by way of example, as formed of wood provided in three laminations, and an interposed drum 9, the heads and drum being secured together as hereinafter described.

The drum 9 which is made of metal may be formed in any suitable way from sheet metal, such as for example sheet steel and more particularly high carbon sheet steel as it is much less

susceptible to denting than the low carbon steels, the ends of the drum in the forming of the latter being drawn to provide shallow, inwardly extending, preferably continuous, flanges 10.

The drum 9 also comprises metal rings 11 located in the drum at its ends, these rings which extend transversely of the drum as shown fitting at their outer margins into the interior annular angles formed at the junctures between the body of the drum and the flanges 10. The rings 11 which may, by way of example, be made of low carbon steel, are of a thickness relatively great compared with the thickness of the sheet metal of the drum 9, and of a depth much greater than the flanges 10 in the particular construction given above as an example, the rings being, by way of example, $\frac{1}{8}$ " or $\frac{1}{16}$ " thick with a depth of from 2" to $2\frac{1}{2}$ ".

The rings 11 are secured to the drum as by tack welding these parts together at intervals say of about 6" either along the inner faces of the rings 11 at the joints between their circumferences and the cylindrical body portion of the drum as represented at 12, or along the outer faces of the rings 11 at the joints between them and the inner edge portions of the flanges 10 as represented at 13.

The heads 7 and 8 and drum 9 are shown as secured together by the tie bolts 14, which extend continuously through openings in the heads 7 and 8, lined with flanged bushings one of which is shown at 15, and through openings, one of which is shown at 16, in the rings 11, the flanges 10 being so shallow as to reach short of a position in which they are intersected by the tie bolts 14.

The provision of the flanges 10 on the drum greatly facilitates the securing of the rings 11 in proper relation to the drum wall rendering unnecessary the continuous seam welding of the rings in position. The flanges 10 to serve their purpose may be made very shallow as disclosed, reaching short of the tie bolts, and this permits the drum to be formed from high carbon sheet steel with the advantages above noted.

The desired thickness of metal at the ends of the drum to resist shear at the bolts 14 may be provided, without regard to the gauge or kind of metal of the drum wall, by reason of the provision of the rings 11 as described. Thus I am enabled to avail myself of the advantage of using high carbon steel for the circular body portion of the drum to prevent denting, while providing the necessary thickness of metal at the bolt holes in the drum to present the desired resistance to

shear; a condition not possible of attainment where the bolt-engaging flanges of the drum are formed by turning inwardly the ends of the metal sheet of which the body of the drum is formed, 5 except by forming the drum wall of such thickness as to render the reel expensive to manufacture and of objectionable weight.

Instead of providing the inwardly projecting separate portions at the ends of the drum as 10 endless one piece members as represented of the rings 11, they may be formed as sectional rings, as for example as illustrated in Figs. 5 and 6. In this construction the rings 11 are replaced by 15 circular series of sections together forming annuli positioned relative to the inwardly extending flanges 10 in the ends of the drum and secured to the drum as shown and explained of the rings 11. One of such series of sections, forming one of the rings, is shown at 17, the sections of which, provided, by way of example, one for each tie bolt with an opening 18 therefor, being in the form of chordal segments 19 which preferably are welded together at their adjacent ends as represented at 20 and more clearly illustrated in Fig. 6, and to the drum either at their 25 inner or outer faces as described of the construction shown in Figs. 1-4.

While I have illustrated and described certain particular embodiments of my invention, I do not 30 wish to be understood as intending to limit it thereto as the same may be variously modified and altered and the invention embodied in other forms of structure without departing from the spirit of my invention.

35 What I claim as new, and desire to secure by Letters Patent, is:

1. A reel comprising a pair of heads, a metal

drum between said heads comprising a relatively thin sheet metal drum-wall-forming portion of stiff dent-resisting material with the sheet metal at the ends of the drum wall turned inwardly to form flanges, ring members adjacent the ends of the drum at the inner sides of said flanges, weld means securing said drum-wall-forming portion and ring members together at spaced apart intervals, and means extending through said ring members for securing together said drum and heads, said flanges reaching short of said last-named means.

2. A reel comprising a pair of heads, a metal drum between said heads comprising a relatively thin sheet metal drum-wall-forming portion of stiff dent resisting steel with the sheet metal at the ends of the drum wall turned inwardly to form flanges, ring members adjacent the ends of the drum at the inner sides of said flanges, weld means securing said drum-wall-forming portion and ring members together, and means extending through said ring members for securing together said drum and heads, said flanges reaching short of said last-named means.

3. A reel comprising a pair of heads, a metal drum between said heads comprising a sheet metal drum-wall-forming portion of stiff, dent resisting metal, with the sheet metal at the ends of the drum wall turned inwardly to form flanges, ring members adjacent the ends of the drum at the inner sides of said flanges, weld means securing said drum-wall-forming portion and ring members together, and means securing together said drum and heads, said last named means passing through said rings and free from contact with the edges of said flanges.

RALPH W. CLEMMONS.
